Helen Tonley.

UNITED STATES PATENT OFFICE

LAURA CHASSELL TOOPS, OF COLUMBUS, OHIO

CHAIR

Application filed December 28, 1928. Serial No. 328,903.

My invention relates to improvements in chairs particularly adapted for infants and young children.

An object of my invention is to provide a chair on which a child may be supported in various positions, a further object of my invention is to provide a chair adjustable to meet the requirements of growth, size and posture in a child at successive stages of development, and of children of different sizes, a further object of my invention is to provide a chair which will serve as a convenience in the care and training of infants and children. Other objects and advantages of my invention will be apparent from the following specification.

I accomplish the above mentioned objects by my invention, a preferred embodiment of which is illustrated in the accompanying drawings, in which

Figure 1 is a plan view of the device,

Figure 2 is a side elevation of the same,

Figures 3, 4 and 5 are views of the graduated seat plates,

Figure 6 is a vertical section of the urinal shield, and

Figure 7 is a front view of the same.

Similar characters of reference refer to similar parts throughout the several views.

My improved device comprises a seat section 1, a back 2, and a leg rest 3, with supporting members. The seat section, back and leg rest are preferably provided with sides 1', 2' and 3' respectively, which serve to support the occupant and prevent him from falling therefrom and also serve as arm rests. The trough like structure thus produced also promotes independence in the child.

The seat section 1, has an opening 4 adapted to receive interchangeable plates 5, 6, 7 and 8, provided respectively with toilet openings 5', 6', 7' and 8' of graduated size which are adapted to the use of a child at successive stages of development from very early infancy as well as to children of various sizes. These plates are interchangeable in the cut out portion 4 of the seat section 1, the side walls of which cut out portion being so shaped as to retain the said plates without permitting them to be accidentally displaced, which may

be by providing flaring side walls or in any other convenient manner. For the purpose of preventing accidental displacement of the plates, I provide a substantially circular cut out portion 4, in the seat section 1 and construct the plates 5, 6, 7 and 8 of like form whereby the plates are surrounded on all sides with a wall which prevents the plates from sliding out of position accidentally and causing injury to the occupant of the chair.

The structure should be built on the basis of actual measurements to attain the best results for child training, and for the purpose of best meeting the requirements, I prefer to provide the smaller opening, as in plate 8, to accommodate a child under two weeks of age and the larger opening, as in plate 5, to accommodate a child of three years of age. Intermediate sizes, as in plates 6 and 7, may be provided to accommodate a child in intermediate stages of development, and may be increased in number and progressively graduated sizes.

On the underside of the seat section 1, I provide a bead or the like to receive and hold, below the seat and the opening thereof, a receptacle, 10, of any suitable form but which is preferably of glass or other transparent or translucent material, which will permit the contents to be observed without removing the child from the seat.

The seat section 1, is provided with supporting legs preferably of the folding type, comprising a pair of legs 11 hinged to the forward portion of the seat section 1 by means of a pin 11' or the like, and extending rearwardly, and a pair of legs 12, hinged to the legs 11 intermediate their ends by a pin 12' and provided at their upper ends with a knife edge 13, adapted to engage the teeth 14 on the under side of the seat section 1, whereby the angle of inclination of the legs and the elevation of the seat may be adjusted.

Links 15, having a slot 16, are secured to the legs 12 by means of pins 15' and are adjustably secured to the leg rest 3 by means of bolts 17 in the slot 16, and a thumb nut, or the like thereon, whereby the leg rest may be frictionally secured in adjustable position.

The leg rest 3 may be secured to the seat

section 1 by means of hinges 18 or the like, and provided with an adjustable foot board 27. I prefer to attain adjustability in this foot board 27 by means of pins 27' thereon adapted to be seated in sockets 25 whereby the foot board 27 may be adjustably positioned toward and from the seat section 1 to accommodate the occupant of the toilet.

The back 2 is of such length as may be required as is indicated by the broken lines in the drawings. It is preferably supported at the desired angle of inclination by means of an adjustable support 19 which is preferably of the telescopic type whereby it may be extended as required, and may be secured to the back section 2 by means of a hinge 19'.

I prefer to secure the back 2 to the seat section 1 by means of pins 20 carried by the back and adapted to be seated in suitable sockets in the seat section 1. Suitable pins 20' or the like, may be provided to frictionally bind the pins 20 in their sockets 21, 22, 23 respectively.

The sockets 21, 22, 23 are so positioned and inclined that, in the various positions thus assumed by the back, the occupant will be in the position best adapted to the use of the toilet opening in the seat. The seat sockets are so placed as to carry the back in a vertical position, a horizontal position and any desired number of intermediate positions therebetween. In very young infants, a horizontal recumbent position is, of course, required and for such infant the back will be positioned in a horizontal position. As the child develops, the back may be raised until the vertical position is reached for older children.

The independent position of the leg rest 40 and foot board 27 permits adjustability as to the needs of a child as may be advised by the pediatrician for evacuation, so that either an erect or right angled position or a squatting position may be provided for.

I have found in my experience that the training of children should begin at a very early period, particularly as to the process of evacuation and that small infants at stool require frequent observation.

Handling or disturbing the child during the process is to be avoided and I therefore prefer to employ a receptacle 10 of glass or other transparent or translucent material whereby the contents may be observed without disturbing or removing the child, and this also facilitates promptness in removal of the contents after elimination, an important feature in training and mental hygiene.

For the purpose of preventing the soiling 60 of clothing and covering thrown over the child and to direct the urine into the receptacle, 10, I provide a urinal shield 29 which rests against the toilet aperture and within it and has an open spout 29' which passes 65 between the legs of the occupant of the chair.

The upper portion 29' of the urinal shield 29 has a wide shell body with an open front adapted to receive the discharge of urine from the child and direct it into the vessel below.

The urine shield 29 and its supporting bracket 30 should be of soft flexible material of such character as not to injure the child if brought into contact with it.

I prefer to support this urinal shield by 75 means of a flexible wire bracket 30 which may be bent to the desired shape for the accommodation of the child.

In Figure 3 I have shown my improved 80 toilet open and extended for use in the recumbent position of the child. It will, of course, be understood that the supporting legs 11, 12 the link 15, and the support 19 are in pairs and that only the side nearer the observer is shown.

I have shown the sides secured to the seat section, back and leg rest by means of hooks and eyes 31, but any convenient form of attaching means may be employed.

The sides 1', 2' and 3' produce a trough 90 like structure which prevents the child from falling from the toilet and thus promotes independence and safety.

While I have called particular attention to the advantages of my improved toilet in the 95 care and training of infants and small children, it is evident that it may be used to advantage in the care and treatment of those suffering from illness or weakness from any cause.

I have thus described the preferred form of my invention but the form shown may be modified and otherwise changed without departing from the spirit of my invention.

Having thus described my invention, what 105 I claim is:

1. In a chair, the combination of a seat section and a back rest, pins on the back rest, and sockets for the pins positioned in the seat section, whereby the back rest may be 110 adjustably positioned on the seat section.

2. In a chair, the combination of a seat section, a back rest, pins on the back rest, sockets for said pins and positioned in the seat section, and a leg rest, side sections thereon producing a trough like structure adapted to support the occupant and means for 115 adjustably positioning the back and leg rest.

3. In a chair, the combination of a seat section, a toilet opening therein, a receptacle of translucent material positioned below the said toilet opening and adapted to permit inspection of the contents of the receptacle without removing the occupant of the chair, a back rest, pins on the back rest and sockets in the seat section adapted to receive the said pins, said sockets being set at angles inclined from the vertical to permit the back rest to be adjustably positioned on the seat section.

4. In a chair, the combination of a seat sec- 130

tion, a toilet opening therein, a receptacle below the said toilet opening, a back rest, sockets in the seat section and set at angles of inclination from the vertical, means on the back rest adapted to engage said sockets in the seat section, whereby the back rest may be adjustably positioned on the seat section.

5. In a chair, the combination of a seat section, a toilet opening therein, a back rest and 10 a leg rest, side sections on the said seat section, back rest and leg rest, producing a trough-like structure, means for adjustably positioning the leg rest, pin means on the back rest and sockets in the seat section adapted to receive said pins to adjustably position 15 the back rest on the seat section.

In testimony whereof I affix my signature.

LAURA CHASSELL TOOPS.
